SAMPLING DEVICE

Thomas V. Moore, Houston, Tex., assignor to
Standard Oil Development Company, a corpora-
tion of Delaware

Application February 7, 1941, Serial No. 377,828

3 Claims. (Cl. 137—166)

The present invention is directed to a device for taking samples of fluid flowing in a conduit.

It is an object of the present invention to devise a sampling means for a flowing stream of fluid which utilizes the energy of the fluid for its operation.

A further object of the present invention is to provide a means for diverting from a flowing stream a sample, the size of which is proportional to the amount of fluid forming the stream.

Other objects and advantages of the present invention may be seen from the following description taken in conjunction with the drawing in which the sole figure is an elevation, partly in section, of a preferred modification of the present invention.

The device of the present invention provides a means for diverting a definite portion of a stream of fluid flowing in a conduit. It depends for its operation upon the known fact that if two conduits containing orifice plates, across which most of the pressure drop in a conduit occurs, are connected in parallel, the ratio of the fluid flowing in each of the lines is constant.

It is known that, if the main line has one orifice plate, the flow can be represented by the equation

$$Q = C\sqrt{h}$$

where Q is the flow, C is $\sqrt{2g}$ times the orifice coefficient and h the pressure drop across the orifice. If the conduit is provided with a bypass line having several plates in series, the following equation is true:

$$q = \left(\sqrt{\frac{1}{C_1^2 + C_2^2 + C_3^2 + \dots}} \right) \sqrt{h}$$

where q is the flow of fluid through the bypass line, C_1, C_2, C_3 etc. are $\sqrt{2g}$ times the plate coefficients, and h the total pressure drop across all of the plates in the bypass line. If the resistance in the bypass line is small compared to the drop across the orifice plates, the total pressure drop across all of the orifice plates in the bypass line is equal to the pressure drop across the orifice plate in the main conduit. Under such conditions, the following equation is true:

$$\frac{q}{Q} = \sqrt{\frac{1}{C_1^2 + C_2^2 + C_3^2 + \dots}} = \frac{1}{C}$$

which, in turn, equals a constant.

The device of the present invention utilizes the above discussed principle.

Referring specifically to the drawing, a casing 11 is provided with a bore 12 and counterbore 13 which together comprise the sampling chamber. Main conduit 14 has arranged therein orifice plate 15. The upstream side is connected to bore 12 by a line 16, and the downstream side is connected to the bore by line 17. Orifice plate 18 is positioned in line 17.

The openings from line 16 into bore 12 and all other similar openings are preferably made in the form of sharp edge orifices in order that the fluid circuit will in effect be a line with a number of orifice plates in series. Arranged within bore 12 is piston valve 19 which is shaped so that it fits slidably within the bore. The center portion of the piston is recessed. Arranged within counter bore 13 for sliding movement therein is piston 20 which has attached thereto longitudinal extending tubular portion 21 provided with inwardly projecting shoulders 22. Longitudinally extending rod 23 is secured to piston valve 19 and is provided with serially arranged lugs 24 and 25. Lug 25 is of greater lateral dimensions than the opening between shoulder 22 and is arranged in the cavity of tubular member 21 between the piston 20 and shoulder 22.

A trigger 26 having attached thereto leaf spring 27 is arranged within the counterbore of the sampling chamber to cooperate with lug 24 and is secured to the casing of the sampling chamber by pivot 28. A spring 29 has one end secured to casing 11 and the other to piston valve 19. A conduit 30 fluidly connects the end of counterbore 13 with bore 12 at a point adjacent the connection of line 16 thereto. Conduit 31 is also arranged for conducting fluid from the bore to sample receiver 32.

When the parts of the device are in the position shown in the drawing, fluid is free to flow from main conduit 14 through branch conduit 16 into bore 12 and the fluid passing around the recessed portion of piston valve 19 is conducted by line 30 into the upper portion of counterbore 11. The pressure of this fluid forces piston 20 downwardly which, in turn, forces fluid through line 17, orifice 18, back into the main conduit 14. When piston 20 has traveled downwardly a predetermined distance, tubular member 21 will release lug 24 from catch 26 allowing spring 29 to pull piston valve 19 from its open to its closed position. When valve 19 closes, its upper enlarged end prevents the entrance of fluid by line 16 and the recessed portion allows lines 30 and

31 to be in fluid communication. Fluid may then flow from the down stream side of main conduit 14 through line 17, orifice 18 and into the sampling chamber to force piston 20 in an upward direction. The upward movement of piston 20 forces fluid through line 30, bore 12 and line 31 out into sample container 32 which may be an open or closed container, as desired, but must be maintained at a pressure substantially below that in conduit 14.

When piston 20 has moved upwardly a predetermined distance, shoulder 22 engages lug 25 and piston valve 19 is drawn upwardly with piston 20. The movement of the piston upwardly continues until valve 19 again uncovers the outlet of line 16 which allows the fluid from the upstream side of conduit 14 to enter in bore 12. However, the device is so proportioned that when the outlet of line 16 is uncovered, the outlet to line 31 has been covered, and trigger 26 is in position to engage lug 24 and hold valve 19 in an open position. The device is accordingly in position to repeat its cycle.

In order to increase the speed of the cycle, fluid from the downstream side of conduit 15 may be allowed to flow into the sample container without passing through orifice 18. However, to allow such a flow of fluid, a bypass 33 has been provided in line 17 leading around orifice plate 18. Bypass 33 contains check valve 34 which allows the flow of fluid from the downstream side of the conduit into the sampling chamber, but prevents the flow of fluid in the reverse direction.

In order to obtain a more satisfactory operation, piston valve 19 and piston 20 should not only be accurately ground to fit into the sampling chamber, but, in addition, piston 20 should have an average density approximately equal to that of the sampled liquid in order to minimize the friction of the piston motion. One method of constructing piston 20 so that it has approximately the average density of the fluid being sampled is to construct it of metal with an interior cavity to reduce its average density.

As has been pointed out above, the amount of fluid flowing through line 17 provided with orifice plate 18 is proportional to the main stream of fluid flowing through line 14 provided with orifice plate 15. If desired, sample receiving vessel 32 may be provided with volume calibrations so that

the total flow of fluid through said conduit for a given period of time may be directly indicated by the size of the sample collected in that period of time.

5 While I have disclosed a specific modification of the present invention, it will be apparent to the skilled worker that various changes in the sizes and proportions of the parts may be made without departing from the scope of the invention. It is accordingly not my intention to be bound by the specific modifications disclosed, but to claim the invention broadly.

I claim:

1. A sample receiving device adapted for removing samples from a fluid carrying conduit provided with a restriction comprising, in combination, a sample receiving chamber, a piston slidably arranged in said chamber, a valve casing, a second conduit arranged for fluidly connecting the space defined by walls of the chamber and one end of the piston with said fluid carrying conduit on the downstream side of said restriction, a third conduit fluidly connecting a second space defined by walls of the chamber and the other end of said piston with said valve casing, a fourth conduit adapted to fluidly connect said valve casing with said fluid carrying conduit on the upstream side of said restriction, a fifth conduit adapted to fluidly connect said valve casing with a sample receiving container, a valve member slidably arranged in said casing to allow fluid communication between said third and fourth conduits when in a first position, and between the third and fifth conduits when in a second position, and a mechanical linkage between said piston and said valve member whereby said valve member is shifted from one position to another by movement of said piston.

2. A device in accordance with claim 1 in which an elastic member is attached to said valve member biasing it to said second position.

3. A device in accordance with claim 1 in which an elastic member is arranged in said valve casing to bias the valve member in said second position and a releasable catch is arranged adjacent said mechanical linkage to hold said valve member in said first position and to be released by contact with said piston.

THOMAS V. MOORE.
